UNITED STATES PATENT OFFICE.

JOHN MICHEL, OF PHILADELPHIA, PENNSYLVANIA.

VULCANIZER.

1,271,055.

Specification of Letters Patent.

Patented July 2, 1918.

Application filed May 25, 1917. Serial No. 170,947.

To all whom it may concern:

Be it known that I, JOHN MICHEL, a citizen of United States, residing at 3013 N. Taney street, Philadelphia, in the county of 5 Philadelphia and State of Pennsylvania, have invented new and useful Improvements in Vulcanizers, of which the following is a specification.

This invention relates to vulcanizers of 10 the type particularly employed for repairing or mending rubber articles.

The primary objects of the invention reside in the provision of an efficient and serviceable vulcanizer of a light and portable 15 nature, inexpensive to manufacture, capable of being easily operated in a correct manner by unskilled persons, not likely to become broken or out of order, and having securing means formed therewith for securely fastening the same to a suitable stationary support in order to be in a position for active 20 operation.

With these and other objects in view, the invention consists in the novel features of 25 construction, combination of elements and arrangement of parts, hereinafter fully set forth in the following description, and the scope of which is indicated by the appended claims.

30 In the drawing—

Figure 1 is a vertical sectional view taken through the preferred form of the vulcanizer comprising the present invention.

Fig. 2 is a transverse sectional view, taken 35 along the line 2—2 of Fig. 1.

Similar characters of reference denote corresponding parts throughout the several views of the drawing.

Referring to the details of the present invention, the letter A designates a vulcanizer 40 constructed in accordance with the invention, the same including a bracket or frame 1, formed to provide an enlarged shelf portion 2. The portion 2 is provided with an 45 integral recess arm 3, suitably braced by means of a web 4. The lower portion of the arm 3 extends parallel with the shelf 2, and is provided with a threaded opening for the reception of a hand-manipulated securing 50 screw 5. In securing the bracket to a stationary support or the like 6, the latter is inserted or positioned within the recess defined between the arm 3 and the shelf 2; then by revolving the screw 5 the frame 1 may be 55 securely clamped to the support and thus retained in a service-imparting position.

When it is desired to secure the frame upon a wall, not shown, or other similar surface, instead of placing the same upon the shelf-like support 6, the frame is provided with laterally extending bifurcated ears 7, which are employed to receive suitable securing elements, not shown, thus providing adequate means for effectively securing the vulcanizer to either horizontally or vertically disposed supporting elements.

Mounted upon the enlarged outer extremity 8 of the shelf 2, and secured to the frame by means of screws or the like 9, is a flue or heating drum 10. The latter is vertically 70 positioned upon the shelf 2 and has the lower end thereof provided with an opening 11. A fuel holder or cup 12 is adapted to be inserted into the drum by way of the opening 11, so as to be centrally located therein, 75 lugs 13 formed with the shelf 2 being employed to facilitate the positioning of the fuel holder within the drum. The holder 12 is preferably hollow in cross section and is adapted to receive a quantity of fibrous 80 packing 14, which may be saturated with alcohol or the like and is retained within the holder by means of a netting 15.

A table or plate 16 is mounted upon the upper extremity of the drum 10, so as to 85 completely cover the latter, depending lugs 17 formed with the table and being employed to engage with the interior wall of said drum, so as to prevent lateral displacement of the plate 16. Set screws or the like 90 18 are threaded into the drum and engage with the lugs 17, whereby the plate will be rigidly secured to said drum. The peripheral edge of the table or plate 16 is provided with depending baffle plates 19, which are 95 located in radial alignment with openings 20 provided in the approximate upper extremity of the drum 10, said opening being utilized to permit gases of combustion, generated by the fuel burner 12, to escape 100 from the drum 10. The plates 19 are employed to deflect such escaping gases so that the same will not come in direct contact with a tire 21 or the like carried by the table, as the heated gases emitted by the drum would 105 have a distinctly detrimental effect upon the tire.

In order to provide means for efficiently securing the tire 21 upon the table 16, and to press a repairing patch 22 in close engagement therewith, use is made of a clamping plate 23, which is adapted to be posi- 110

tioned or located immediately above and in alignment with the plate 16. The clamping plate is provided with a centrally disposed enlarged boss 24, which is adapted to receive the lower extremity of a pressure screw 25. The latter is threadedly mounted within a bearing 26 integrally formed with a yoke-shaped arm 27 of the bracket 1. An enlarged manipulating head is carried upon 10 the upper extremity of the screw 25 and is employed to conveniently operate the latter. From the foregoing description it is thought that the operation of the invention will be readily understood. When the vulcanizer has been connected with a support, as shown in Fig. 1, the damaged portion of the tire or article to be repaired is covered with the soft rubber patch 22, and is placed on the heating table 16. The pressure screw 25 is then operated to force the plate 23 into firm engagement with the tire, so that the latter cannot slip or move over the surface of the heating table. After this has been accomplished the fuel in the 20 cup or holder 12 is ignited, and allowed to burn until all of the same has been consumed, which will complete the process of vulcanizing the patch 22 with the tire 21. Subsequent to this operation the parts are 25 allowed to cool, and the tire may then be removed from engagement with the vulcanizer, and will be in an efficiently repaired condition.

From the foregoing description, taken in 30 connection with the accompanying drawing, it will be apparent that a vulcanizer for the purpose set forth has been provided which, though comprising few parts, is highly efficient and practicable for achieving the objects specified.

Having thus described the invention what is claimed as new is:

1. In a vulcanizer, the combination with a frame, a vertically extending heating 45 drum mounted upon the frame and having an opening in the wall thereof, a fuel cup adapted to be positioned within the drum through the opening to rest upon the frame, a heating table closing the upper extremity of the drum, said drum having exhaust openings adjacent the upper end, baffles depending from the peripheral edge of the table to deflect the heat escaping through the openings, a clamping plate coöperating 50 with said table to impart pressure upon articles positioned upon the table, means for effecting an adjustment of said clamping plate, and means formed on the frame for attaching the latter to either a vertical 55 or horizontal support with the drum vertically disposed.

2. In a vulcanizer, the combination with a frame having a horizontally disposed ledge, means for securing the frame to a vertical or horizontal support, a heating 65 drum secured to the frame and having one end resting upon the ledge, said drum having an opening in the front thereof, a burner adapted to rest upon the ledge and positioned within the drum through said 70 opening, a table closing the upper end of the drum and detachably secured thereto, said drum having exhaust openings adjacent its upper edge, baffle plates depending from said table for deflecting the heat escaping from the drum through said openings, a combined clamping and bracing element, and a frame carried screw for controlling the action of said element for the purpose specified. 80

3. In a vulcanizer, the combination with a frame including a horizontal ledge, a heating drum reposing upon said ledge and vertically disposed, said drum having an enlarged opening, a burner adapted to be positioned within the drum through said opening to rest upon said ledge, lugs rising from the ledge and coacting with the burner to maintain the latter in proper position within the drum, a table closing the upper end of the 90 drum, said drum having exhaust openings adjacent its upper end, baffle plates depending from said table for deflecting heat escaping from the drum through said openings, a yoke shaped arm formed on the 95 frame, a tire clamping and bracing plate, and an adjusting screw threadedly associated with the yoke for controlling the action of said plate.

4. In a vulcanizer, the combination with 100 a frame having a horizontally disposed ledge, a heating drum supported endwise upon said ledge, a burner supported upon said ledge within the drum and spaced from the walls of the latter, said drum having 105 heat exhaust openings adjacent its upper end, a table closing the upper end of the drum, lugs depending from the table and engaged against the inner wall of the drum, fastening elements carried by the drum, 110 and engaging said lugs for removably holding the table in proper position upon the latter, baffles depending from said table for deflecting the heat escaping from the drum through said openings, a combined clamping and bracing plate arranged above the 115 table, and means for adjusting said plate to impart pressure upon articles positioned upon the table.

In testimony whereof I affix my signature. 120

JOHN MICHEL.
